PROTECTIVE GARMENT

Mabel J. Gundy, Chicago, Ill.

Application September 16, 1954, Serial No. 456,387

5 Claims. (Cl. 2—187)

The present invention relates to protective garments, and more particularly relates to a protective garment to protect the garments and/or coiffure of a person from such conditions as rain and the like.

Protective garments embodying the principles of the present invention enjoy particular utility in such uses as rain hoods or capes or combinations thereof as well as aprons and the like, in addition to being quite efficient for these purposes and most economical to manufacture. These garments, made in accordance with the principles of the present invention, are preferably comprised of a sheet of flexible water repellent material such as a plastic material or the like of which the polyvinyl materials such as polyvinyl chloride or a polyvinyl acetate are noteworthy examples.

In accordance with the principles of the present invention, by accordion pleating a sheet of such material and securing the ends of the pleats or folds together by such means as a grommet or rivet or the like and further securing to the folded sheet, by the same grommet or rivet or the like, a tie ribbon, there may be provided a rain hood which may be expanded to cover a wearer's head with or without a hat, and which may be refolded by a simple snapping action so that the sheet may be further folded to a very small and compact package having a peripheral dimension about the same as that of a playing card, for storage in an appropriate size bag of similar material.

The invention may further be embodied in a similar device to which there is attached as an integral part thereof, a further sheet of similar material so that when the folds are expanded the hood portion may rest on the wearer's head while the further sheet will cover the neck and shoulders as a cape. This further embodiment of the invention is also operative to be worn as an apron or the like.

One of the distinctive features and objects of the present invention lies in the attachment of the tie ribbon to the garment. This tie ribbon may be provided by setting a single length of ribbon into one of the folds of the accordion folded sheet and then grommeting or riveting the ends of the ribbon together with the folds by the same rivets or grommets. Thereafter, cutting of the ribbon transversely in about the center thereof will permit the ribbon to be removed from the fold as a tie ribbon.

By setting the grommets or rivets into the material rather loosely, they may act as hinges for moving the ribbon into and out of the appropriate fold in which it was originally placed. This feature of the loose rivet or grommet, in addition to conveniently securing the tie ribbon to the protective garment, has the additional improved feature of permitting convenient and easy replacement into the fold after use, so that when the garment is folded up for placement in its small storage bag, the ribbon will not detract from the easy and convenient folding of the garment.

It is, therefore, an important object and feature of the

2

present invention to provide a new and improved protective garment.

Still another object of the present invention is to provide a new and improved protective garment which is operable as a rain hood or cape or both and which is further utilizable as an apron or the like.

Still another object of the present invention is to provide a new and improved protective garment formed from a sheet of flexible water repellent material wherein the sheet is accordion folded and the ends of the folds are secured together by grommets or rivets or the like.

Still another object of the present invention is to provide a new and improved protective garment formed from a sheet of flexible water repellent material wherein at least a portion of the sheet is accordion folded and the folds are secured together by a loose grommet or rivet or the like which further secures thereto a pivotally mounted flexible tie ribbon.

Still other objects, features and advantages of the present invention will become readily apparent from the following detailed description of the present invention and preferred embodiments thereof, from the claims, and from the accompanying drawings in which each and every detail shown is fully and completely disclosed as a part of this specification, in which like reference numerals refer to like parts, and in which:

Figure 1 is a diagrammatic illustration of a combination protective garment embodying the principles of the present invention and shown in place tied onto the head of a wearer;

Figure 2 is an elevational view of the garment illustrated in Figure 1;

Figure 3 is a fragmental expanded and enlarged sectional view of an accordion pleated portion of the garment of Figure 2 and viewed as taken substantially along the line III—III;

Figure 4 is an illustration of still another form of protective garment embodying the principles of the present invention and shown expanded and in place on the head of a wearer;

Figure 5 is a plan view of the garment of Figure 4; and

Figure 6 is an exploded view of these garments folded for placement into a convenient size storage bag and shown together with the storage bag or envelope.

As shown on the drawings:

There is illustrated in Figure 1 an embodiment of the present invention wherein the device is operable to be used as protective head wear and more particularly as a protective cape and hood to be worn over the head, neck and shoulders of the wearer. This combination device 10 is illustrated as having a hood section 11 and a cape section 12 which are integral and further have connected thereto tie strings or ribbons 13 which will tie the device onto the wearer 14 and more particularly under her chin to retain the same on the wearer and protect her against inclement weather conditions.

This protective garment may be formed from any flexible water repellent material but is preferably formed from such thin plastic sheet material as those in the polyvinyl group such as a polyvinyl chloride or a polyvinyl acetate or the like. As stated, however, any other desired flexible water repellent light weight material may be employed in protective garments embodying the principles of the present invention.

The hood portion 11 of the garment 10 is formed by accordion pleating or folding of at least a portion of the sheet forming the garment 10 such as illustrated in Figure 3 wherein it is shown that the sheet forming the hood portion 11 is folded with accordion pleats or folds 15—15 longitudinally thereof.

The ends of the pleats or folds are secured together by

such means as a grommet or rivet 16—16 which will hold the pleats or folds together at the ends thereof and retain the folded shape for the hood 11. The cape portion 12 of the garment 10 may be formed from the same sheet as that from which the hood 11 was formed, or it may be formed as a separate sheet having a dimension substantially the same as that of the hood and being secured to an end fold of the hood section by such convenient means as an appropriate cement or by dielectric heating and/or induction welding or the like, as at 17. This cape portion 10 12 may further be expandable for a greater width along the bottom edge 18 thereof than along the top edge 19 thereof by providing a few pleats 20—20 therein which will be permanently set therein by securing the upper edges thereof in the same manner as that employed in securing the cape 12 to the hood 11.

With the accordion folded hood section and the cape section integrally secured together or formed from a single sheet they are adapted to be worn as a combination rain hood and cape by expanding the central region of the hood section so that it can open into a cup shape and be tied onto the head of the wearer by the tie strings 13.

In accordance with the principles of the present invention these tie strings may be most conveniently and easily assembled together with the accordion pleated hood section by disposing a single length of ribbon between a pair of folds 15—15, as at 21, Figure 3, and securing the same in that position by means of the grommets or rivets 16. Thereafter, cutting the ribbon in its central region as at 22, Figure 2, will release the tie strings 13—13 for pivotal movement outwardly to the position shown in solid lines in Figure 2.

To this end, the grommets or rivets 16—16 are relatively loose and permit the ribbon to pivot thereabout. At the same time, the various folds 15—15 of the hood section 11 may also be pivoted about the grommets or rivets 16—16 to permit more effective expansion of the accordion folded or pleated hood section 11 as is shown in Figure 1.

This combination garment 11 may be refolded from its expanded position to the accordion folded position by a simple snap action which may be effected by grasping the rivets or grommets 16—16 and pulling the same to a spaced position. The forces exerted on the hood section 11 will then cause the hood section to refold to its accordion folded position.

Thus, it will readily be seen that the protective garment illustrated in Figure 1 is readily utilizable as a rain hood and cape and is economical to manufacture, in addition to being convenient and easy to use and refold.

This combination garment 10 also has an additional feature of being utilizable as a convenient apron or the like with the cape section forming an apron and the hood section, while folded, forming a waist-band with ties 13—13.

A subcombination modified form of the invention is shown in Figures 4 and 5 wherein a rain hood 10' is shown on a head of a wearer, in Figure 4. This rain hood 10' is otherwise substantially identical to the hood section 11 of the garment 10 of Figures 1 through 3 and has grommets or rivets 16 holding the accordion folds 15 together at the ends thereof and together with tie strings 13, all of which are pivotal about the axis of the rivets or grommets 16. This hood is formed substantially identically to the hood 11 so that the tie strings 13—13 are placed within a fold or between a pair of folds 15—15 and secured therein by the rivets or grommets 16—16 and then cut in the central region thereof as at 22.

Further, this hood may be refolded after having been expanded for wear, by simply exerting tension on the hood as by grasping the rivets 16—16 and separating the same to their maximum separation.

When so refolded, this hood and cape or the simple hood may be folded to a very small set of dimensions so that it may be placed in a relatively small envelope or

bag such as the bag 23 of Figure 6. This bag may also be formed of the same material as that from which the hood and/or cape are formed and by the provision of snap fastener 24 the bag may be sealed and the entire garment conveniently, easily and safely carried in the pocket or purse of the possessor thereof.

From the foregoing it will be readily observed that numerous other modifications and variations may be effected without departing from the true spirit and scope of the novel concepts and principles of my invention. I therefore intend to cover all such modifications and variations as fall within the true spirit and scope of the novel concepts and principles of my invention.

It will be understood that modifications and variations may be effected without departing from the scope of the novel concepts of the present invention.

I claim as my invention:

1. A protective garment comprising a first sheet of flexible water impervious material, said first sheet having a plurality of accordion-like folds longitudinally arranged therein along substantially parallel equidistant lines, the end folds of said first sheet forming attaching edges therefor, a second sheet of flexible water impervious material having top and bottom edge portions, said top edge portion forming an attaching edge for said second sheet, said second sheet having its attaching edge secured along its entire length to one of the attaching edges of said first sheet of folds, rigid means securing said folds together at the end portions thereof, whereby the folds in the end portions thereof secured by said rigid securing means may be turned relatively thereto and said folds between the end portions thereof may be expanded by the wearer to form a cup-like protective hood and the two sheets secured to the wearer as a combination hood and cape type garment.

2. A protective garment comprising two sheets of flexible water impervious material, the first sheet having a plurality of accordion-like folds longitudinally arranged therein along substantially parallel equidistant lines, the end folds of said first sheet forming attaching edges therefor, rigid means loosely securing said folds together only at the end portions thereof, the second sheet of flexible water impervious material having top and bottom edge portions, said top edge portions forming an attaching edge for said second sheet, said second sheet having its attaching edge heat sealed along its entire length to one of the attaching edges of said first sheet, a ribbon tie means secured between the intermediate folds within the end portions thereof by the rigid means securing the folds together, whereby the ribbon tie may turn about said rigid means and said folds between the end portions may be expanded and the two sheets tied to a wearer as a cup-like hood and cape protective garment.

3. A protective garment comprising two sheets of flexible water impervious material, the first sheet having a plurality of accordion folds longitudinally arranged therein along substantially parallel lines, the end folds of said first sheet of folds forming attaching edges therefor, the second sheet having top and bottom edge portions, said top edge portion forming an attaching edge for said second sheet, said second sheet having its attaching edge secured along its entire length to one of the attaching edges of said first sheet, said second sheet extending downwardly away from said first sheet to form a cape, rigid means securing said folds loosely together at the ends thereof and ribbon tie means secured to said first sheet intermediate and at the ends of the folds therein operative to be secured together whereby the folds may be turned and expanded by the wearer relative to said rigid means and the two sheets secured to a wearer as a combination cup-like hood and cape when the folds are expanded by the wearer.

4. A protective garment comprising a first sheet of flexible water impervious material, said first sheet having a plurality of accordion-like folds longitudinally ar-

ranged therein, the end folds of said first sheet forming attaching edges therefor, a second sheet also of flexible water impervious material having top and bottom edge portions, said top edge portion forming an attaching edge for said second sheet, said second sheet having its attaching edge integrally secured along its entire length to one of the attaching edges of the first sheet, rigid rivet-like means pivotally securing said folds loosely together only at the ends thereof, and ribbon tie means pivotally secured to the first sheet by said rivet-like means, whereby the folds in the end portions may turn and the folds intermediate the end portions thereof may be expanded by the wearer and the two sheets secured to the wearer with the folds expanded as a combination hood and cape protective garment.

5. A protective garment comprising a first sheet of flexible water impervious material, said first sheet having a plurality of accordion-like folds longitudinally arranged therein, the end folds of said first sheet forming attaching edges therefor, a second sheet also of flexible water impervious material having top and bottom edge portions, said top edge portion forming an attaching edge for said

5 second sheet, said second sheet having its attaching edge integrally secured to the entire length of one of the attaching edges of the first sheet of folds forming a cape, rigid-like means pivotally securing said folds of the first sheet together only at the ends thereof, and ribbon tie means pivotally secured to said first sheet by said rivet-like means, whereby said two sheets may be secured to the wearer as a protective garment.
